By Edward V. Pagelske
Attorney

UNITED STATES PATENT OFFICE.

THOMAS H. KANE, OF YOUNGSTOWN, OHIO, ASSIGNOR TO TRUSCON STEEL COMPANY, OF YOUNGSTOWN, OHIO, A CORPORATION OF MICHIGAN.

FORM FOR FLOORS.

Application filed April 24, 1922. Serial No. 556,243.

The forms constituting the subject matter of this application are intended to produce air spaces in concrete slabs and are usually placed end to end in parallel rows 5 with concrete above and between them.

In my prior Patent No. 1,065,449, dated June 24, 1913, a form for floors is shown of open box-like shape in which the top has a plurality of main depending transverse ribs 10 and a series of secondary ribs between the main ribs and at substantially right angles thereto. These forms have generally been found satisfactory, but in some cases, as where the form is to support a heavy dead 15 load before the concrete has set, these patented forms are not sufficiently stiff, and the present invention has for its object the production of a form which shall embody no more material than do the patented forms 20 of the same general dimensions, but which shall be capable of carrying a much heavier load with the same deflection.

In the accompanying drawing, Fig. 1 is a diagram showing the original corrugations 25 of the top of this sheet metal form in dotted lines and the deep ribs formed therein which are to give this form sufficient strength. Fig. 2 is a plan of a completed form. Figs. 3 and 4 are sections on the lines 30 3—3 and 4—4 of Fig. 2 respectively.

Similar reference characters refer to like parts throughout the several views.

The form shown in the drawing is produced from a sheet 1 of corrugated material, 35 the original corrugations being transverse to the sheet as indicated at 2 in the several figures. The sheet is bent twice along lines at substantially right angles to the corrugations, the bends 3 being gradual. The 40 sides 4 of the form may be at any desired angle to the top but I prefer them to be approximately at right angles thereto.

At the time the sheet is bent, the metal 45 which is to constitute the top of the sheet 50 form is pressed between dies to produce a series of parallel corrugations or grooves, one corrugation or groove across the top for every two corrugations of the original sheet, the sides of adjacent grooves 55 being united to each other and to the sides of adjacent corrugations by means of substantially cylindrical strips extending parallel to the grooves. The two sides of adjacent

corrugations and the cylindrical strip uniting them form a rib 5, and as all the material of the top 6 is used in producing these ribs 5, the stiffness of the finished form is much greater than that shown in the prior patent.

Fig. 4 shows the ends 7 of the ribs 5 to 60 be of less depth than the middle, but the depth there shown is sufficient as these points are so near the supporting side walls 4. This construction also permits these forms to be bent along the lines 3 so that 65 the sides may be at any desired angle to the tops and the lower edges of these sides may be moved toward and from each other to produce the desired air spaces and serve 70 as proper molds for the concrete beams 75 which are to extend between adjacent rows of these forms.

The sizes and proportions of these forms and the spacing and depths of the ribs and corrugations therein may all be changed by 75 those skilled in the art without departing from the spirit of my invention as set forth in the following claims.

I claim:—

1. A sheet metal form of open box-like 80 shape for producing air spaces in floor slabs, comprising a top and sides integral therewith, said sides having substantially evenly spaced vertical corrugations, the top having evenly spaced transverse corrugations less 85 numerous and deeper than the corrugations of the sides, the corrugations of the top comprising substantially flat sides at an angle to each other integrally connected to each other and to the sides of adjacent corrugations by means of substantially cylindrical strips parallel to said corrugations of the top.

2. A sheet metal form of open box-like 90 shape for producing air spaces in concrete slabs, comprising a top and sides integral therewith, said sides being formed with substantially evenly spaced vertical corrugations, the top being formed with transverse 95 grooves less numerous than the corrugations of the sides, the sides of adjacent grooves being united by means of substantially cylindrical strips extending parallel to the grooves.

THOMAS H. KANE.
